(57) **CLAIM**

The ornamental design for an electronic apparatus with integrated movable display, as shown and described.

DESCRIPTION

FIG. 1 is a front, right, top-side perspective view of a first embodiment of the electronic apparatus with integrated movable display showing my new design with the integrated display in an open position;

FIG. 2 is a front, right, top-side perspective view thereof with the integrated display in a closed position;

FIG. 3 is a front elevational view thereof;

FIG. 4 is a right side elevational view thereof, the left side elevational view being a mirror image thereof;

FIG. 5 is a rear elevational view thereof; and,

FIG. 6 is a top plan view thereof.
